DESIGN FOR A DRESS

Gilbert Rosenberg, New York, N. Y.

Application September 15, 1936, Serial No. 64,866

Term of patent 3½ years

To all whom it may concern:

Be it known that I, Gilbert Rosenberg, a citizen of the United States of America, residing in city of New York, county of New York, and State of New York, have invented a new, original, and ornamental Design for a Dress, of which the following is a specification, reference being had to the accompanying drawing, forming part thereof.

I claim:

The ornamental design for a dress substantially as shown.

GILBERT ROSENBERG.
